CIGARETTE HOLDER AND PIPE STEM

Samuel Segal, New York, N. Y.

Application May 21, 1931. Serial No. 538,966

6 Claims. (Cl. 131—12)

The present invention pertains to improvements in a cigarette holder or pipe stem and has for one of its objects to provide a construction comprising complementary elements which may 5 be quickly assembled in compact relationship characterized by an air tight seal to preclude leakage between contiguous contacting faces thereof and as another object the invention comprehends a device which may be readily separated whereby access may be had to the interior of the elements collecting saliva and other juices deposited therein for quickly removing the objectionable deposits by washing and cleansing in any well known fashion.

15 More particularly the invention contemplates provision of means for supporting one end of a cigarette in a pocket defined by split complementary elements having corresponding flat faces mutually held in contacting relation after 20 assembly by a casing or jacket.

Another object is to provide novel means associated with a cigarette support for quickly discharging the cigarette member therefrom.

Specifically, another object is the provision of 25 an insert with one complement thereof in threaded association with a casing, while another complement is frictionally held to the casing, although it is within the scope of the invention to provide each complement of the aforementioned insert with means for frictionally and wedgeably connecting with the interior surfaces 30 of the casing.

Another aspect and a further advantage thereof is in the provision of a split insert comprising 35 complementary elements which require no special adjustment to assemble preparatory to being secured and held in proper relation by the casing.

Broadly speaking, the invention aims to provide 40 a split insert having contiguous parts in contact and held in such contact by a unitary device having an interior surface adapted to snugly and wedgeably contact the exterior surface of said insert and comprising in association 45 with the aforesaid device in reality a one piece member for carrying into effect the purposes of the invention.

A further object comprehends the provision 50 of a novel pipe bowl adapted to be sealed in air tight fashion by a split stem of complementary parts held in operative relation by a casing mounted at one end thereof.

Still another object and feature of the invention 55 is to provide a construction having few parts which are easy and fool proof to assemble pro-

viding a compact unitary arrangement which in turn may be readily disconnected into its parts for proper cleansing.

Another advantage of my invention is to improve a cigarette holder or pipe stem which may 30 be manufactured at a relatively small cost.

The invention aims further, as above intimated, to improve generally and enhance the utility of devices of that type hereinafter more particularly set forth.

The invention is exemplified in the combination and arrangement of parts shown in the accompanying drawing and described in the following specification and it is more particularly pointed out in the appended claims.

Referring to the drawing:

Fig. 1 is a longitudinal sectional view of a cigarette holder.

Fig. 2 is a side view of the cigarette supporting end of the holder illustrated in Fig. 1.

Fig. 3 is a side view of the mouth piece end of the holder shown in Fig. 1.

Fig. 4 is a section taken along the line 4—4 of Fig. 1.

Fig. 5 is a sectional view of a modification.

Fig. 6 is a sectional view taken along the line 6—6 of Fig. 5.

Fig. 7 is a longitudinal view of one complement of the insert in Fig. 5.

Fig. 8 is a longitudinal but inside view of the other complement of the insert of Fig. 5.

Fig. 9 shows a section of a modified insert.

Fig. 10 is a section taken along the plane 10—10, Fig. 9.

Fig. 11 is an elevational view, partly in section of a pipe and an associated stem.

Fig. 12 is a view taken along the line 12—12 of Fig. 11 in the direction of the arrows.

It will be apparent from the teachings of the present disclosure that the embodiments herein set forth are merely suggestive of the type of constructions that may be employed in carrying the invention into effect, as other suitable devices for a like purpose but of different construction having an arrangement of different elements may be employed in carrying out the principles of the invention. Referring more particularly to the cigarette holder illustrated in Figs 1—4 inclusive, 10 generally designates a casing comprising a unitary member including the longitudinally disposed cylindrical and tapering bore

11, with the narrow end thereof at the mouth piece end 12 of the casing and its longest gage 110 at the insert receiving end 13 which has been

countersunk and threaded as illustrated for a purpose hereinafter set forth.

For increasing the ornamental appearance of the casing the latter preferably has the mouth piece portion elliptical having its narrower gage or dimension adjacent the guard 14, however, gradually increasing its gage therefrom until the elliptical surface merges with the cylindrical surface 14' substantially half the distance between the ends of the casing and from that point the other half of the casing has an outer cylindrical surface.

Associated with the casing and disposed within the tapering bore thereof is the cigarette supporting split insert, broadly denoted 15, which comprises complementary juxtaposed elements 16 and 17 defining the longitudinal bore generally referred to, as 18 adapted to conduct the fumes or smoke from the cigarette (not shown) to the user. The complementary elements illustrated in Figs. 1-4 inclusive may be interchangeable and are similar as to details in their construction and for this reason a description of one is thought will suffice. Each element embodies a longitudinally disposed groove 19, and an outer smooth, curved and tapering surface and is further provided with an enlarged portion or threaded neck 21 to cooperate and engage with the countersunk threaded portion 13 of the casing and an extension with flat gripping faces 22' or cigarette receiving portion 22 including a depression as 23 adapted for supporting the cigarette member in pocket 26 defined by the depressions when superimposed as illustrated, it being noted that the extension of each complement comprises a stop or semi-annular shoulder 25 extending beyond or overhanging the casing which stop limits movement of the insert within and against the casing.

To provide an air or smoke tight seal between the complementary elements of the insert, each element and extension thereof includes a smooth flat face as 24 on both wings as 26' of its respective groove, the corresponding adjacent faces of the juxtaposed elements mutually contacting, which engagement is preserved to provide a leak proof joint by the casing or encompassing member 10 after the complements of the insert have been assembled with their flat faces abutting and thrust into the casing after which the latter is threaded against the threaded portions of the complements. With the complements secured in the casing, it will be noted that the mouth piece ends thereof lie flush with the end plane of the casing and further that the outside tapering curved surfaces of each complementary element bears snugly in engagement with and against the curved inside tapering surface of the casing, and in this relation the shoulders 25 are against the end wall of the casing. It is thus apparent that not only is the transverse leakage prevented between the complementary elements, but additionally transverse leakage cannot take place between the insert and the casing.

To secure a cigarette in the holder, the split parts of the insert are first disconnected from the casing, one end of the cigarette being placed in a depression or seat of an extension of one element, the other depression of the associated complementary element is placed in registry over the cigarette and the insert carrying the cigarette is bodily moved inwardly being clamped in the pocket constituted by the superimposed depressions and as the casing and the neck members 21 are connected, the shoulders or stops 25

are against the casing whereby the flat adjacent faces of the elements are held snugly in contact, being maintained in such contact by the clamping action of the casing.

If it is desired to discharge the cigarette from the insert the latter is first unthreaded and one complement is slidably moved forwardly with respect to the other and the cigarette falls off without any need of the operator touching or picking the cigarette.

As illustrated in Fig. 1, each of the components of the insert is provided with a threaded enlarged neck 21 and each wing as 26' with flat and uninterrupted faces as 24. With the modification shown in Figs. 5-8 inclusive, only one component of the insert is provided with an enlarged threaded neck portion as 30 while the other component includes a uniformly smooth uninterrupted circular but tapering outside surface extending from the undercut shoulder 31 of the extension 32 to the end face 33 of the terminal 34, it being noted, however, in this instance that the shoulder 31 although below the upper surface of the casing still provides a stop to limit the movement of the casing along the insert or vice versa, bearing in mind that the gap formed between the shoulder 36 and the adjacent end wall of the casing serves to permit a finger nail of the operator therein.

In this way, by applying an outward force against the shoulder 36, element 15 will be slidably moved to the position indicated by the dotted lines as shown in Fig. 5 thereby, discharging the cigarette member even though, the other element is retained by the casing.

It will be understood that although I have shown in Fig. 5 but one element having a smooth outside curved and tapering surface, both of the elements may be similarly constructed, (see Fig. 9) namely with smooth curved tapering surfaces, the elements apart from their enlarged extensions as 22 or 32 constitute a frustoconical bored body when assembled being uniformly tapering with the outside entire surface thereof after assembled mutually and frictionally engaging the inner surfaces of the casing, the entire length 120 thereof.

Further distinguishing in construction over the embodiment of Figs. 1-4, the insert of Figs. 6-10 inclusive comprises an element with a longitudinally disposed indentation 39 in each wing 40, while the contiguous element contains a longitudinally disposed rib or bead 43 in each wing as 44 on the opposite side of its respective axial groove 45. The ribs of one component are guided by and may be slidably moved along the adjacent indentations with the contiguous flat faces of the complements as well as the surfaces of the beads and their corresponding grooves, in contact thereby preventing any transverse leakage transversely of the insert.

In Figs. 9 and 10, a supplementary lock may be provided for the enlarged split contacting extensions as 22, which when assembled have an outer contour, octagonal in shape, as in Fig. 2, but one extension of the insert is provided with a small but rounded protuberance 45' adapted to be received by indent 46 of the other complement, one extension being so arranged, that an outward thrust applied to the shoulder 47 will separate the elements to eject the cigarette previously retained in the pocket 23 defined by the extensions as is well understood, it being further noted that each complement of the insert contains a continuously and uninterrupted smooth and tapering but curved outside surface, and when the elements

are assembled, the outer surfaces thereof are frictionally and wedgeably retained by the inner wall of the casing.

As heretofore mentioned, the invention in its broader aspects may be applied to a pipe in which 5 50 designates the bowl provided with the integral extension 51 for frictionally receiving the stem broadly denoted 52 which includes split complementary elements 16 and 17 having flat faces 53 and 54 in contact providing an air or gas tight seal. It will be noted that the upper element 17 is perforated as at 56 while the lower element embodies a curved portion 58 defining a wall which 10 closes in seal tight fashion opening 59 of the bowl 15 50.

The elements of the insert have a curved intermediate portion 60 and are held together to preclude air or gas leakage by the removable jacket 61, it being understood, of course, that the octagonal intermediate and enlarged portion 62 of the 20 insert limits the extent to which the latter may be moved into the extension or arm 51 of the pipe and that the tobacco may be suitably packed above and around the perforated upper element. 25 Thus it is apparent that the pipe stem may be readily removed from the bowl and quickly detached and cleansed. With the pipe stem removed, the bowl may be also easily cleansed.

The foregoing disclosure has been given by way 30 of preference for clearness and understanding. Hence no unnecessary limitations should be understood and the appended claims should be construed as broadly as the state of the art permits.

I claim:

35 1. In combination, an insert comprising complementary elements, a casing having means to snugly engage the outer surfaces of said elements, one of said elements having a supplementary connection with said casing, the other element being 40

slidably associated with respect to its complement and including means for disengaging thereof from said casing.

2. In combination, an insert comprising complementary elements for supporting a member, a casing having means to snugly engage the outer surfaces of said elements and means to retain one element secured to said casing during actuation of its complement to eject said member. 80

3. In combination, an insert comprising complementary contacting elements for supporting a member, a casing for maintaining said elements in contact, and means for slidably moving one element with respect to the other in discharging said member. 85

4. In combination, a bored insert comprising complementary separable contacting elements for supporting a member, an enlarged portion on each element, the enlarged portions of said elements being juxtaposed and defining a pocket in which said member is retained in operative position, and a unitary device frictionally and threadably connected with at least one of said elements. 90

5. In combination, an insert comprising complementary juxtaposed elements, an enlarged portion on each element, a casing, stop means associated with each element to limit movement thereof in said casing, one of said stop means including an undercut portion for moving one of said elements with respect to the other. 100

6. In combination, an insert comprising complementary juxtaposed elements, an enlarged portion on each element defining a pocket, a casing, means for slidably moving one element with respect to the other for overhanging said casing, and 110 complementary locking means on said portions to maintain said elements in operative relation. 105
